UNITED STATES PATENT OFFICE

ARTHUR WM. NELSON, OF PARK RIDGE, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed June 18, 1928. Serial No. 286,441.

This invention relates generally to improvements in locomotive boilers and more particularly to a construction which is advantageous in that type of boiler having a firebox wherein fuel is burned in suspension and the invention consists of the matters hereinafter described and more particularly pointed out in the appended claims.

One of the objects of the present invention is to provide a novel water heating and circulating arrangement which partially bottoms the firebox and includes a pair of water tables, one connected to and extending downwardly and inwardly from each side water leg to join with a common header, that is in turn connected to the front throat of the boiler. Another object of the invention is to so form the elements that the air necessary to support combustion in suspension is admitted through parts of each element and preferably one on each side of the header common to both elements.

Still another object of the invention is to provide a structure of this kind, which with only a minor change, is adapted to employ either a single or double fuel nozzle so that conditions in different sizes of fire boxes may be readily accommodated.

These objects of the invention as well as others together with the many advantages thereof will more fully appear as I proceed with my specification.

In the drawings:

Fig. 1 is a longitudinal vertical sectional view through the firebox end of a locomotive boiler embodying one form of my invention.

Fig. 2 is a horizontal sectional view through the same as taken on the line 2-2 of Fig. 1, with the firebrick, burner and associated parts omitted to better disclose the construction and arrangement of the water seaming and circulating elements and associated header.

Fig. 3 is a transverse vertical sectional view through the firebox end of the boiler as taken on the line 3-3 of Fig. 1.

Fig. 4 is a view on an enlarged scale, similar to the bottom portion of Fig. 3 and showing a modified form of construction.

Referring now in detail to that embodi-

ment of the invention illustrated in Figs. 1 to 3 inclusive of the accompanying drawings, 1 indicates as a whole the barrel of the boiler in which are arranged the usual flues 2. The firebox of the boiler is formed by the flue sheet 3, rear sheet 4, side sheets 5-5 and crown sheet 6 all connected together in the manner well known. The bottom portion 3^a of the flue sheet forms the throat sheet of the firebox.

The firebox wrapper comprises the top plate 7, the side plates 8-8, the outside throat plate 9 and the outside back plate 10. The wrapper just described, together with the firebox sheets before mentioned, define the several water legs of the boiler, i. e., the side legs 11, the front leg or throat 12, and back leg 13 all closed at the bottom by the usual mud ring 14. The firebox sheets are joined to the wrapper plates by means of staybolts 15 in the manner well known. 16 indicates a door opening which is normally closed by a door (not shown). This opening provides the fuel door opening in case the firebox is converted into a coal burner as is sometimes necessary and which conversion may be readily made with but comparatively small expense.

In the middle bottom portion of the firebox I provide a novel water steaming and circulating means indicated as a whole by the numeral 17 in Fig. 2. Said means comprises a pair of laterally spaced flat hollow elements 18-18 which are each connected at one end to an associated side sheet of the firebox, and extend downwardly and inwardly therefrom to terminate in longitudinally spaced branches 19-19. The branches of each element are connected to opposite sides of a header 20 disposed in the longitudinal median plane of the firebox. This header which is closed at its rear end, extends beyond said elements at its front end, where it is curved upwardly to form an intake neck 21 that is connected to front throat sheet 3^a. Preferably said header which is of an elliptical cross section of substantially large diameter is staybolted as at 22 throughout its length to amply resist internal pressures and the extreme front end thereof is suitably secured

in a flexible diaphragm 23 in the throat sheet 3^a. This diaphragm is positioned a suitable distance above the mud ring so as to make conversion from one type of firebox to the other, practical.

5 The arrangement described occupies a substantial area in the bottom of the firebox and the branches of each element together with those portions of the header between said branches provide air inlet openings 24—24 necessary to support proper combustion.

10 As before stated, the elements are arranged in the mid-portion of the firebox so that the front and rear ends thereof are spaced from the like ends of the firebox. The 15 space to the front of said elements is closed by a front or burner wall 25 and the space to the rear of said elements is closed by a rear or flash wall 25^a both walls being made of firebrick. In the front or burner wall there 20 is located, one on each side of the intake neck of the header, fuel nozzles 26—26 which are directed inwardly and downwardly toward the midportion of the firebox. Said nozzles 25 as shown herein are of the oil burner type and project through suitable openings 27 in said walls as best indicated in Fig. 1.

25 The elements 18—18 are provided at those ends which are connected to the side sheets 5—5 with top, bottom and end flanges 28 which fit in openings in said side sheets and are butt welded thereto as at 29 and certain of the stay bolts 15 employed between the side sheets and associated side plates 8, connect 30 said flanges to said side plates as best shown in Fig. 3. So that said elements may amply 35 withstand the internal pressures generated in use for their intended purpose I staybolt said elements as indicated at 30.

40 In Fig. 4 I have illustrated a slightly modified form of construction wherein the intake end 21 of the header 20 is formed for connection with two different points in the throat sheet 3^a. As shown said intake end has two 45 diverging tubular branches 21^a—21^a respectively, each fixed at its extremity in diaphragms 23^a—23^a in said throat sheet. Under such conditions only a single burner nozzle 26^a is employed and said nozzle is positioned in the burner wall 25^b midway between said branches 21^a—21^a. To assist in 50 supporting the header and elements, I provide one or more straps 31 which are fixed at their ends to the side portions of the mud ring 14 and each has a central seat in which the header engages.

55 In operation, the intense heat from the fuel burning in suspension, over the said elements and header, causes a rapid absorption 60 of heat by the upper sides thereof, which in turn passes to and is absorbed by the water in said elements and header, thus converting part of it into steam. Because of the inclined positions of the elements, a rapid flow 65 of water into the side water legs of the boiler

is produced. That is to say water flows from the throat of the boiler into the header and then through the branches 19—19 into the elements 18—18 and from there into said side water legs. Thus the header and elements provide a relatively large superficial area which is exposed to the radiant heat of the fuel burning in suspension in the firebox.

70 The structures described are confined to firebox dimensions so that they do not interfere with the numerous other parts of the locomotive and they are so disposed in the firebox that they are not subjected to such widely different temperature changes as would cause them to be affected by the resulting strains and stresses.

75 The arrangement of said parts is such that they may be readily removed from the firebox when necessary so that the firebox may be changed to a coal burner with a minimum 80 amount of labor.

85 While in describing my invention, I have referred in detail to the construction, form and arrangement of the parts thereof I do not wish to be limited thereto except as may be specifically pointed out in the appended claims.

90 I claim as my invention:—

1. A locomotive boiler construction embodying therein a firebox having side sheets 95 and a throat sheet, a pair of relatively flat hollow water circulating and steaming elements, each being affixed at the top end to and opening through an associated side sheet and extending downwardly and inwardly therefrom and a header connected at one end to said throat sheet and positioned at its other end between said elements and connected to each element at longitudinally spaced points thereof and providing air inlet openings for the firebox between said points of connection, said elements and header coacting to substantially close the bottom of the firebox.

100 2. A locomotive boiler construction embodying therein a firebox having side sheets 105 and a throat sheet, a pair of relatively flat hollow water circulating and steaming elements each affixed at their outer ends to and opening through an associated side sheet and extending downwardly and inwardly to terminate in longitudinally spaced branches, and a header coacting with said elements to substantially close the bottom of the firebox, said header being connected at one end to said throat and positioned at its other end between the branches of each element and which are connected to said end of the header, portions of said header and portions of said elements between said branches, providing 110 air inlet openings for the firebox.

115 3. A locomotive boiler construction embodying therein a firebox having side sheets and a throat sheet, a pair of relatively flat hollow water circulating and steaming elements, each being affixed at the top end to 120

and opening through an associated side sheet and extending downwardly and inwardly therefrom and a header positioned at one end between and connected to the bottom inner 5 ends of said elements and having diverging branches at its other end opening through and connected to said throat sheet, said elements and header coacting to substantially close the bottom of the firebox.

10 In testimony whereof, I have hereunto set my hand, this 31st day of May, 1928.

ARTHUR WM. NELSON.
